COMBINED HANDLE AND ESCUTCHEON PLATE

John Pawl, Rte. 30 and 55, Crown Point, Ind.

Filed June 8, 1962, Ser. No. 70,468

Term of patent 14 years

(Cl. D10—8)

Fig. 1

Fig. 2

FIGURE 1 is a front elevational view of a combined handle and escutcheon plate embodying my new design; and

FIGURE 2 is a side elevational view thereof.

The subject application is a continuation-in-part of my abandoned application Serial No. D-62,530, filed October 18, 1960.

The rear of the escutcheon plate shown in FIGURE 1 is substantially flat and unornamented.

The characteristic feature of my design resides in the conformance in configuration between the ends of the handle and the ends of the plate, as shown.

I claim:

The ornamental design for a combined handle and escutcheon plate, substantially as shown and described.
